UNITED STATES PATENT OFFICE.

JOSEPH SANDUSKY, OF NEW YORK, N. Y.

BALL LOOP.

Application filed December 30, 1922. Serial No. 608,901.

To all whom it may concern:

Be it known that I, JOSEPH SANDUSKY, a citizen of the United States, residing at New York, in the county of New York and State of New York, have invented certain new and useful Improvements in Ball Loops, of which the following is a specification.

My invention relates to electric light fixtures, and one of the objects of the invention is to provide connecting means between the electric light and its support, which can be readily placed in position.

Another object of the invention is to provide a connection which will conceal the electric wires from view.

A further object is to provide a universal joint which will permit the lamp to be swingably connected to its support and at the same time will prevent such rotation as would cause twisting and breaking of the electric wires.

With these general objects in view, my invention consists in certain novel and peculiar features of construction and combination of parts as hereinafter described and claimed, and in order that it may be fully understood, reference is to be had to the accompanying drawing, in which

Figure 1 shows a light suspended from a chandelier, the connection being shown in section;

Fig. 2 is a perspective view of the preferred form of connection, the parts of the coupling being shown separated;

Fig. 3 is a transverse section along the lines 3—3 of Fig. 2, corresponding to the line 3—3 of Fig. 4;

Fig. 4 is an elevation of the ball and socket connection.

At the present time, the prevailing method of attaching electric lamps to chandeliers is by means of chain links, which leaves the electric wires open to view. In pulling the wires through the apertures of the connections, located at the ends of the links in the chandelier and the lamp, they are pulled at such an angle as to sometimes cut the insulation on the electric wire. By the pro-

tection of the improved connections, the wires are concealed from view, and in pulling them straight through the connection, there is no danger of cutting the insulation.

In the drawing, 1 represents the conventional chandelier suspended by chains 2 and

carrying on its outer edge lamps 3. For securing the lamp to the chandelier, I provide a universal connection, which may be of the ball and socket type, as shown in Fig. 1. The ball section 4 may be turned up from any suitable metal, such as brass, and at the opposite end is provided with a screw thread 5 for engagement with a complementary screw threaded aperture 6 carried by the lamp. The socket section 7 is also provided with a screw threaded end 8 for engagement with a complementary screw threaded aperture 9, which is formed in the end loop 10 of the supporting chain. Both the ball and the socket sections are provided with flanges 11, which serve to limit the movement of the screw threads in their final position and also furnish a satisfactory means for holding and turning the parts, while assembling the same. Extending through the joint and longitudinally of its axis are conduits 12 and 13, for the passage of the electric wires 14 which lead to the lamp.

To prevent turning of the joint around its longitudinal axis and which would take place in the case of an ordinary ball and socket joint, with the result of twisting of the electric wires and breaking the insulation, I provide an improved construction, which will permit the lamp to swing freely, without rotating around the longitudinal axis of the joint.

When the ball and socket joint is used, the side of the ball is milled off to provide a flat surface 15. The side of the socket section is provided on its inner side with a surface that is out of alignment with the spherical inner side, so that contact therewith of the flat side 15 of the ball will limit rotation about the longitudinal axis of the joint. The eccentricity of the socket may be attained by merely bending in the metal of the socket to provide a projection 16.

It will be understood that the cooperating parts of each joint fit loosely and have sufficient play so that the suspended lamp will freely take a vertical position by its own weight.

From the above description it will be apparent that I have produced a device of the character enumerated as desirable, and while I have illustrated and described the preferred form of the invention, it will be understood that I reserve the right to all

changes properly falling within the spirit and scope of the appended claims.

I claim:

1. An electric light fixture comprising a support and an electric lamp provided with screw threaded openings, a coupling for connecting the lamp to the support comprising two short tubular members, a ball at one end of one of the said members engaging a socket at one end of the other member, the connection between the said ball and socket being freely movable and loosely fitting, screw threads at the outer ends of said members, adjacent to the said ball and socket, the said threads adapted to engage the said openings, the part of the coupling secured to the lamp adapted at all times when in operative position to normally assume a vertical position, a cut-away portion on the ball and an eccentric portion on the socket, the said portions cooperating to prevent substantial rotation of the ball and socket about the longitudinal axis of the joint but permitting free swinging movement.
2. An electric light fixture comprising a support and an electric lamp provided with screw threaded openings, a coupling for connecting the lamp to the support comprising two short tubular members, a ball at one end of one of the said members engaging a socket at one end of the other member, the connection between the said ball and socket being freely movable and loosely fitting, screw threads at the outer ends of said members, adjacent to the said ball and socket, the said threads adapted to engage the said openings, the part of the coupling secured to the lamp adapted at all times when in operative position to normally assume a vertical position, a flat portion on the side of the ball and an inwardly projecting portion on the socket, the said portions cooperating to prevent substantial rotation of the ball and socket about the longitudinal axis of the joint but permitting free swinging movement.

In testimony whereof I affix my signature.

JOSEPH SANDUSKY.
